UNITED STATES PATENT OFFICE.

HENRY M. RENNER, OF JUNCTION CITY, KANSAS.

SHOE-CLOSURE.

1,314,284.

Specification of Letters Patent. Patented Aug. 26, 1919.

Application filed January 23, 1919. Serial No. 272,755.

To all whom it may concern:

Be it known that I, HENRY M. RENNER, a citizen of the United States, residing at Junction City, in the county of Geary and 5 State of Kansas, have invented certain new and useful Improvements in Shoe-Closures; and I do hereby declare the following to be a full, clear, and exact description of the invention, such as will enable others skilled in 10 the art to which it appertains to make and use the same.

This invention relates to improvements in shoe closures and has for one of its objects the provision of a device of this character 15 whereby the use of hooks, or projections for closing or securing together the closure flaps of the shoe is obviated, thereby preventing fraying of dresses or trousers or the interference with the polishing process of the 20 shoe.

Another object of this invention is the provision of spaced flat hooks secured to the inner faces of the closure flaps of the shoe adapted to receive the shoe strings from the 25 inner faces thereof, whereby the tedious process of threading eyelets and the fraying of garments is obviated.

A further object of this invention is the provision of a shoe closure of the above 30 stated character which shall be simple, durable and efficient, and which may be manufactured and sold at a comparatively low cost.

With these and other objects in view as 35 will become more apparent as the description proceeds, the invention consists in certain novel features of construction, combination, and arrangement of parts as will be hereinafter more fully described and claimed.

For a complete understanding of my invention, reference is to be had to the following description and accompanying drawing, in which:

Figure 1 is a front elevation of a shoe 6 closure constructed in accordance with my invention.

Fig. 2 is a fragmentary sectional view illustrating the manner of securing the hooks to the inner faces of the securing flaps of a 10 shoe upper.

Fig. 3 is an enlarged detail sectional view of one of the hooks illustrating the manner of securing the same to a strip of leather secured to the inner face of the flaps of the 15 shoe,

Fig. 4 is a sectional view taken on the line 4—4 of Fig. 1,

Fig. 5 is a fragmentary view partly in section of one of the hooks.

Referring in detail to the drawing, the numeral 1 indicates a shoe upper having the usual closing flaps 2, to which my invention is applied. Strips of leather or other suitable material 3 are stitched or otherwise secured to the inner faces of the closure flaps 60 adjacent the edges thereof. Hooks 4 constructed from flat resilient material consist of a body portion 5 which is riveted or otherwise secured to the strips of leather 3 as 65 illustrated at 6 and have one of their ends 70 disposed angularly as illustrated at 7 to engage one edge of the strip to prevent fraying thereof. The body portions 5 are bent upon themselves in spaced relation to form 75 resilient tongues 8 which tongues are disposed over the faces of the strips 3 in spaced relation thereto so that a shoe string 9 may be passed under the tongues 8 into the curved portion 10 which is enlarged and slightly rounded so that the shoe string can work 80 freely therein when released and drawn taut. Nibs 11 are formed upon the bodies 5 adjacent the portions 10 for engaging the other edges of the strips to prevent the strips from 85 fraying and also preventing the shoe string from coming in contact with the strips thereby binding the movement of the same. The nibs are slightly inclined so that in removing the shoe string 9 from the hooks, it 90 will be caused to freely ride over the edge of the strip 3. The string receiving portion 10 of the hook is disposed inwardly from the edge of the flap 2 of the shoe so that the same is not visible from the exterior of the shoe. The free end of the tongue 8 is slightly 95 curved away from the strip and projects beyond the strip so that the string can be readily inserted and removed from under the tongue when desired. The upper ends of the strips 3 are left free from the closure 100 flaps 2 of the shoe upper 1 and provided with eyelets 12 to receive the ends of the shoe string 9 so that they may be tied together on the inner faces of the closure flaps thereby 105 providing an invisible tying means of the string for the shoe.

From the foregoing description taken in connection with the accompanying drawings, it will be noted when hooks of the above described character are secured to the inner 110

faces of the closure flaps 2 of the shoe upper, the shoe string may be readily laced into the hooks and the ends thereof tied invisibly after passing them through the eyelets 12. 6 By having the hooks placed upon the inner faces of the closure flaps 2 the edges of the closure flaps are permitted to be drawn in close proximity to each other making a neat appearance to the shoe which is very desirable.

10 While I have shown and described the preferred embodiment of my invention, it will be understood that minor changes in construction, combination, and arrangement of 15 parts, may be made without departing from the spirit and scope of the invention as claimed.

What I claim as new is:—

1. The combination with a shoe upper including closure flaps, of strips of material secured to the inner faces of the closure flaps adjacent their edges, hooks secured to said strips for receiving a shoe string to secure the flaps together, and means formed upon said hooks for engaging the edges of the strips to prevent fraying thereof.

2. The combination with a shoe upper including closure flaps, of strips secured to the inner faces of the closure flaps, flat resilient hooks secured to the strips between the same and the inner faces of the closure flaps for receiving a shoe string to secure the flaps together, nibs formed upon the hooks for engagement with the edges of the strips to prevent fraying thereof and the binding of the shoe string thereagainst.

3. The combination with a shoe upper including closure flaps, strips secured to the inner faces of the closure flaps adjacent their edges, hooks secured to said strips for receiving a shoe string to secure the flaps

together, said strips having their upper ends free from the closure flaps, eyelets carried by the upper free ends of the strips for receiving the ends of the shoe string to permit the shoe string to be tied together upon the inner faces of the closure flaps.

4. The combination with a shoe upper including closure flaps, strips of leather stitched to the inner faces of the closure flaps adjacent their free edges, strips of resilient metal disposed between said strips of leather and the inner faces of the closure flaps and extending transversely of the strips of leather, said strips of resilient metal being bent upon themselves in spaced relation to form resilient tongues, said resilient tongues being disposed over the faces of the strips in spaced relation thereto and having their free ends slightly curved to permit a shoe string to be inserted under the tongues, the curved portions of the strips of metal that form the tongues being enlarged to receive the shoe string to permit the same to slide freely therein.

5. The combination with a shoe upper including closure flaps, of strips of material secured to the inner faces of the closure flaps adjacent their free edges, resilient members riveted to said strips of material, resilient tongues formed on said members and disposed over said strips in spaced relation to receive the shoe string, and said tongues projecting beyond the edges of the strips and slightly curved to permit the easy insertion of a shoe string thereunder.

In testimony whereof I affix my signature in presence of two witnesses.

HENRY M. RENNER.
